GESELLSCHAFT, KUMMLER & MATTER, OF AARAU, SWITZERLAND, A SWISS
CORPORATION.

ELECTRIC SOLDERING-IRON.

1,361,032.

Specification of Letters Patent.

Patented Dec. 7, 1920.

Application filed April 8, 1920. Serial No. 372,343.

To all whom it may concern:

Be it known that I, FERDINAND EICHENBERGER, a citizen of the Swiss Confederation, and residing at Aarau, Switzerland, have 5 invented a certain new and useful Improvement in Electric Soldering-Irons, of which the following is a specification.

This invention relates to electric soldering-irons, and a primary object is to provide 10 a construction wherein a heater can be readily inserted into the head of the iron in such a manner that its heat is efficiently transferred to the bit.

An electric soldering-iron according to the 15 invention comprises a head preferably of aluminium, that has a bore running in the direction of the handle, and a cut extending in the same direction and opening into the bore, and an electric heater fitting into and 20 clamped in the bore.

The invention consists in the construction, arrangement and combination of parts described hereinafter and pointed out in the 25 claims.

One embodiment of the invention is illustrated by way of example in the accompanying drawing, wherein:—

Figure 1 is a side elevation of one form of 30 electric soldering-iron according to the invention,

Fig. 2 is an end elevation thereof,

Figs. 3 and 4 are longitudinal section, and 35 end elevation, respectively, showing the electric heater, and

Fig. 5 is a longitudinal section showing means for connecting the heater to a supply of current.

Like reference letters designate like parts throughout the several views.

An aluminium head *b* of a soldering-iron 40 has a cylindrical bore *m* into which fits a cylindrical heater *a* of refractory heat-conducting material which comprises a resistance wire *n* and is surrounded by a layer *o*

of heat-insulating material. The underside 45 of the head *b* is cut open in the longitudinal direction of the bore, so that two lugs spaced apart are provided. A copper soldering-bit *d*, preferably divided in the vertical plane

x-y indicated in Fig. 2, is inserted from 50 below between these lugs. One single screw *c* serves for clamping the bit *d* between the

said lugs, and the heater *a* in the bore *m*. The latter is closed by end covers *g* and *h* let into the two ends of the head *b*.

55

Two pins *i* are provided diametrically opposite one another in the heater parallel with its longitudinal axis, to which pins the ends of the resistance *n* are connected. The pins *i* are electrically connected with current supply leads *p* by connectors *k*, as clearly shown in Fig. 5. In order as far as possible to prevent loss of heat by the head *b*, its top and sides are covered with a layer *e* of heat insulating material, such as asbestos, which in turn is covered with sheet metal *f*.

60

65

It will be appreciated that the described soldering-iron has the advantage that its heater can be readily inserted in its correct 70 position fitting into the head of the iron, so that efficient transference of heat from it to the head *b* and its bit *d* is assured.

I claim:—

1. In an electric soldering-iron, the combination of a head having a bore extending 75 in the direction of the handle, which head has an extension at substantially right angles to the axis of the head, said extension being provided with a cut that opens into, 80 and extends in the same direction as, the said bore, an electric heater clamped in said bore, and a bit secured in said cut, substantially as set forth.

2. In an electric soldering-iron, the combination of a head having a cylindrical bore extending in the direction of the handle, and having two lugs at substantially right angles to the axis of the head spaced apart disposed in the same said direction as the bore, 85 an electric heater fitting into said bore, a bit fitting into the space between said lugs, and means clamping the heater in said bore and the bit between said lugs, substantially as set forth.

90

3. In an electric soldering-iron, the combination of a head having a bore extending in the direction of the handle, which head has in one side a cut that opens into, and extends in the same direction as, said bore, 100 a bit secured in said cut, and an electric heater clamped in said bore, which heater comprises a resistance wire and two pins that are connected with the latter, and pro-

95

100

ject outward from one end of the heater, substantially as and for the purpose set forth.

4. In an electric soldering-iron, the combination of an aluminium head having a cylindrical bore, and two lugs spaced apart on one side thereof extending in the axial direction of the head, an electric heater fitted into said bore, a bit fitted between said lugs, two cover plates fitted one on each end of the head and closing said bore, and a

screw arranged in said lugs for clamping said heater in said bore and said bit between said lugs, said heater comprising a resistance wire, and two connecting pins that are 15 connected to the ends of the latter and extend through one of said cover plates, substantially as set forth.

In testimony whereof, I affix my signature.

FERD. EICHENBERGER.
